UNITED STATES PATENT OFFICE.

HARRY C. WATSON, OF PITTSBURGH, PENNSYLVANIA, ASSIGNOR TO KEYSTONE MACHINE & ENGINEERING COMPANY, OF PITTSBURGH, PENNSYLVANIA, A CORPORATION OF PENNSYLVANIA.

SHEARING DEVICE.

Application filed December 17, 1921. Serial No. 523,168.

To all whom it may concern:

Be it known that I, HARRY C. WATSON, residing at Pittsburgh, Allegheny County, Pennsylvania, have invented a new and useful Improvement in Shearing Devices, of which the following is a full, clear, and exact description.

My invention relates broadly to shearing devices, and more particularly to mechanism 10 for shearing hollow articles, especially pipe and tubing.

My invention is particularly useful in cutting what is known as "crop" from the ends of pipe. By the use of this invention the 15 crop is cut from the pipe in strip form and, if desired, may be simultaneously corrugated. This operation is carried out by a simple machine and without the use of a mandrel. By employing my invention the 20 bearings for the shafts carrying the shears may be close enough to the same, to adequately support the shears as distinguished from machines as heretofore constructed wherein the shafts carrying the shears were 25 extended from the bearings a distance equal to maximum length to be cut from the pipes. This construction is made possible by reason of the provision of cutters starting their cut from one edge.

30 My invention will be better understood upon reference to the following description taken in connection with the accompanying drawings, forming part thereof, and in which:

35 Figure 1 is a side elevation of one form of machine embodying my invention;

Figure 2 is a plan view of the machine of Figure 1;

40 Figure 3 is a section on the line III—III of Figure 2;

Figure 4 is an end elevation;

Figure 5 is a detail of construction, and

Figure 6 is another detail of construction.

45 Referring to the drawings, a machine embodying this invention may comprise rotating shears 1 and 2. The shear 1 is mounted upon a shaft 3, journaled at 4 and 5, and rotated by power gear 6, through a shaft 7, provided with two universal joints 8 and 9.

50 The section of the shaft upon which the gear 6 is mounted is journaled at 10 and 11 in a supporting frame or casing 12. A pinion 13 is mounted on the shaft 3 and meshes with a pinion 14 on the shaft 15, which shaft

carries the shear 2. The shaft 15 is journaled at 16 and 17 in a supporting housing 18. Rollers 19 are provided above the shear 2 for holding the pipe in position, each of these rollers 19 being controlled by a set screw 20. When moved to the proper position, these rollers are securely fastened by bolts 21, passing through slots 22, in the supporting means for the rollers.

The shaft 3 is threaded at its outer end, and a nut 23 is screwed thereon to hold the shear 1 in place. A set screw 24 bears against the end of the shaft 3, so as to adjust the longitudinal position of the shaft in order to bring the shears in proper relation to each other. The screw 24 passes through a portion 25 of a second supporting housing 48 hereinafter described.

The section of the shaft which carries the power gear 6 also carries a gear 26, which meshes with the gear 27 on a shaft 28, which is provided with a clutch 29, as shown in Figure 3. The clutch 29 is arranged to connect the shaft 28 with a shaft 30, on which is mounted a gear 31, shown in detail in Figure 5. The gear 31 meshes with the gear 32, carrying an eccentric pin 33, mounted in a block 33^a, which slides in a slot in a rack 34 having teeth which mesh with the gear segment 35, for a purpose which will appear later.

55 The shear shafts 3 and 15, are so mounted in the supporting housings carried by the frame 12 that the axes of said shafts may be changed angularly relative to that of the pipe or other article being sheared. The axes of the shafts 3 and 15 remain parallel to each other, and the arrangement of the mounting is such that the shafts 3 and 15 may be pivotally moved around trunnions 46 projecting in opposite directions from the housing 48. The axes of the trunnions pass through the shearing point of the shears. The reason for this arrangement will more clearly appear under the description of the 60 operation of the device.

65 The housing 18 in which is journaled the shaft 15 is supported at one end on a rod 47 which rests on the housing 48. The housing 18 is adjusted by an adjusting screw 49 which is screwed through a portion 50 of the housing 48, the end entering into said housing 18 and arranged to support the same as shown in Figure 3. The upper portion 70

of the screw 49 passes through an arcuate slot 49' in the frame 12 to allow for the movement of the parts around the trunnions 46. By turning the screw 49 the upper 5 shear 2 may be adjusted vertically relatively to the shear 1, the housing 18 in such cases moving around the rod 47 as a pivot. The teeth of the gears 14 and 13 are such as to allow for such adjustment.

10 The parts of the universal joints 8 and 9 are so arranged as to allow for the necessary effective lengthening of shaft 7 when the parts are moved around the trunnions 46.

15 The clutch 29 is operated by a treadle 36, through a clutch rod 37.

Means may be provided for corrugating the crop cut from the pipes in order to produce, in effect, a crush test fulfilling inspection requirements regarding the weld in 20 the pipe. This may be accomplished by corrugating rolls 38 and 39, which mesh with each other, as shown in Figure 4. These corrugating rolls 38 and 39 are mounted on shafts 40 and 41, respectively. The shaft 25 40 is mounted in a movable housing 42 having a pivoted connection 42' at one end and supported at the other end by springs 43. The shaft 41 is driven from shaft 51 which in turn is driven by gears 52, 53 and 54 30 actuated by power gear 6. The shaft 40 is driven from a gear on the shaft 51 which meshes with a gear 55 on the end of the shaft 40. The teeth on these gears are long enough to remain in mesh when the members 35 42 move upwardly due to the passage of the crop between the corrugating rolls.

The pipe to be cropped is moved into the machine over a suitable support 44, shown in Figure 1.

40 The operation of my device is as follows: The pipe to be cropped or trimmed is introduced into the machine in the position indicated by the dotted lines 45, Figure 2. At that time, the shear shafts 3 and 15 have 45 been moved around the trunnions 46 to the position shown in Figure 2, so that the longitudinal axis of the pipe is at an angle to the axes of the shear shafts. The shear 2 operates on the interior of the pipe and 50 the shear 1 on the exterior. By reason of the angular relation of the pipe to the shears, the cut is at a corresponding angle to the axis of the pipe, and as the shears are rotated, the pipe is automatically fed 55 into the shears by the shears themselves and the crop is cut off in the form of a flat ribbon, cut spirally from the pipe. This operation is contained until the desired length has been cut from the pipe, where- 60 upon the clutch 29 is thrown in and the rack 34 is moved to rotate the shear shafts around the trunnions 46 to bring their axes into line with the axis of the pipe whereby the end of the pipe may be finished and 65 squared. The crop is conducted from the

shears to the corrugating rolls 38 and 39 through the opening between the sides of the movable housing 42, and from there to any desired point. The springs 43 permit the rolls 38 and 39 to separate sufficiently to allow the crop to pass between them, but are strong enough to corrugate the crop. The compression of the springs may be changed by suitable nuts.

70 My invention has many advantages, among which may be mentioned that the shear may be used for cutting the pipe, without the necessity of mounting the shear on an extended shaft equal to the length of the part of the pipe to be cut off. The shear which operates on the interior of the pipe is carried by a shaft having bearings relatively near the shearing point, so that the shearing strain is easily carried by the shaft and its supporting members. By reason of the strip formation of the crop, crushing of the pipe is avoided. With a shear, the crystallization of the metal produced by a saw is prevented, as a result of which the pipe is not injured by the cutting operation. The use of a shear is more economical than that of a saw (which has heretofore been the only practicable method used), in that no elaborate safety devices are necessary to protect the workmen from the action of the saw, and considerable space is saved on that account. It will also be apparent to those skilled in the art that by the present invention, scrap pipe, tube and the like may be cut into strip form and the strips used for reinforcing or other purposes, thereby making a salable by-product from scrap material.

100 Many other advantages will be apparent to those skilled in the art. While I have shown and described one embodiment of my invention in detail, I desire it to be understood that I am not to be limited to the exact arrangement shown and described, as many changes may be made in the details without departing from the spirit of my invention.

I claim:

110 1. A pipe cutting machine including an arcuately adjustable shear head having rotary power driven shears thereon, means for effecting the arcuate adjustment of said head and for retaining it in adjusted position, whereby said shears may effect an angular or directly transverse cutting of a pipe irrespective of the axial position of the pipe with respect thereto.

115 2. A pipe cutting apparatus including a pipe support, a shearing head arcuately adjustable with respect to the support, power driven shears on the head, and gearing for effecting an arcuate movement of the head, said head being adjustable to a position wherein the shears are at an acute angle to the axis of the support.

120
125
130

3. A pipe cutting apparatus including a pipe support, a shearing machine head movable in an arc with respect thereto, rotary shears on the head, mechanism for rotating the shears, mechanism for effecting the arcuate movement of said head, and a driving connection between the shear operating means and the head adjusting mechanism, whereby the movement of the head in an arc 10 may be effected synchronously with the rotation of the shears to insure accurate trimming of the pipe.
4. A pipe cutting apparatus including a pipe support, a shearing machine head movable in an arc with respect thereto, rotary shears on the head, means for adjusting the rolls in the head, pipe engaging rolls associated with the shears, mechanism for rotating the shears, mechanism for effecting 20 the arcuate movement of said head, and a driving connection between the shear operating means and the head adjusting mechanism, whereby the movement of the head in an arc may be effected synchronously with the rotation of the shears to insure accurate trimming of the pipe.
5. In a machine for cutting pipe, the combination of a shear for operating on the exterior of the pipe, a shear for operating 25
- on the interior thereof, a shaft for driving said shears, a universal joint in said shaft, and means normally holding the shears in adjusted position for moving said shears around a pivot in a vertical line passing through the shearing point, substantially as 30 described.
6. In a machine for cutting pipe, the combination of shears, shafts for driving said shears, universal joints in one of said shafts, and means normally holding the shears in 35 adjusted position for changing the cutting angle of said shears around a pivot in a vertical line passing through the shearing point, substantially as described.
7. In a rotary shearing mechanism, shear 40 shafts, a shear carried by each of said shafts, a housing in which one of said shafts is journaled, a second housing supporting said first mentioned housing, a pivotal connection between said housings, means for rocking the first mentioned housing about said connection, and means for simultaneously swinging both of said housings, substantially 45 as described.

In testimony whereof I have hereunto set 50 my hand.

HARRY C. WATSON.
